(57) **CLAIM**

The ornamental design for a folding cane, as shown and described.

DESCRIPTION

FIG. 1 is a front perspective view of a folding cane, showing the new design in the folded position;

FIG. 2 is a front perspective view of the folding cane, showing the new design in the extended position;

FIG. 3 is a left view of the folding cane in the folded position;

FIG. 4 is a right view of the folding cane in the folded position;

FIG. 5 is a rear view of the folding cane in the folded position;

FIG. 6 is a front view of the folding cane in the folded position;

FIG. 7 is a top view of the folding cane in the folded position;

FIG. 8 is a bottom view of the folding cane in the folded position;

FIG. 9 is a left view of the folding cane in the extended position;

FIG. 10 is a right view of the folding cane in the extended position;

FIG. 11 is a rear view of the folding cane in the extended position;

FIG. 12 is a front view of the folding cane in the extended position;

FIG. 13 is a top view of the folding cane in the extended position; and,

FIG. 14 is a bottom view of the folding cane in the extended position.

Surface lines are used in the drawings. The surface lines are not to be understood as conveying a particular material or surface finish for any part of the folding cane.

(Continued)

The broken lines depict portions of the article that form no part of the claimed design.

1 Claim, 8 Drawing Sheets
